(57) **CLAIM**

The ornamental design for a hanging sign, as shown and described.

DESCRIPTION

The hang right sign has a hook integrally formed on the upper edge of the sign panel so that it can be conveniently hung in place and removed such as on the inside of an automobile window and the like.

FIG. 1 is a front elevational view of a hanging sign showing my new design. The back view is a mirror image.

FIG. 2 is a left view thereof.

FIG. 3 is a right view thereof.

FIG. 4 is a top view thereof; and,

FIG. 5 is a bottom view thereof.
